RIDING MOWER FRAME

Mario F. Fernandez and Robert L. Rydeen, St. Paul, Minn., assignors to Toro Manufacturing Corporation, Minneapolis, Minn.

Filed Aug. 30, 1971, Ser. No. 176,435

Term of patent 14 years

Int. Cl. D15—03

U.S. Cl. D40—1 R

FIG. 2

FIG. 6

FIG. 3

FIG. 5

FIG. 4

FIG. 1

FIG. 1 is a perspective view of a riding mower frame embodying our new design;

FIG. 2 is a top view thereof;

FIG. 3 is a side view thereof;

FIG. 4 is a bottom view thereof;

FIG. 5 is a rear view thereof; and

FIG. 6 is a front view thereof.

We claim:

The ornamental design for a riding mower frame, as shown and described.
